Primary Examiner — Antoine D Davis(74) *Attorney, Agent, or Firm* — Riverside Law LLP(57) **CLAIM**

I claim the ornamental design for a measuring device, as shown and described.

DESCRIPTION

FIG. 1 is a left side view of a measuring device;

FIG. 2 is a right side view thereof; and,

FIG. 3 is a top view thereof.

The broken lines form no part of the claimed design.
